UNITED STATES PATENT OFFICE.

HARRY G. AINSWORTH, OF KENTLAND, INDIANA

MEANS FOR OPERATING DOORS.

1,418,420.

Specification of Letters Patent. Patented June 6, 1922.

Application filed May 2, 1921, Serial No. 466,252.

To all whom it may concern:

Be it known that I, HARRY G. AINSWORTH, a citizen of the United States, residing at Kentland, in the county of Newton and State 5 of Indiana, have invented certain new and useful Improvements in Means for Operating Doors, of which the following is a specification, reference being had to the accompanying drawings, and to the reference 10 characters marked thereon, which form a part of this specification.

This invention relates to means for operating doors. One of the principal objects of my invention is to provide a simple electro-mechanical apparatus to be installed in buildings where doors are to be operated, and when closed, remain locked in closed position by the means provided for closing the same.

20 Another object of the invention is to provide a conveniently located switch which upon being actuated, will close an electric circuit and start the mechanism for operating the door or doors.

25 Yet another object of the invention is to provide an automatic means whereby the electric circuit will be broken when the actuating means has operated to open or to close the door or doors a predetermined distance.

30 To the attainment of the foregoing objects, the invention consists in the devices and combinations of devices illustrated and described, and more particularly pointed out in the appended claims.

35 In that form in which I have chosen to illustrate the present invention, Fig. 1 is a view taken on the inside of a building equipped with my invention, the doors being shown in elevation, closed.

40 Fig. 2 is a top plan view of the device, the brackets for holding it being shown in section, taken upon the plane of the line 2-2 of Fig. 1.

Fig. 3 is a side view, enlarged, of the device.

45 Fig. 4 is a vertical sectional view, enlarged, taken upon the plane of the dotted line 4-4 of Fig. 2.

Fig. 5 is a plan view, showing a modification.

50 In the drawing, A represents the inside wall of a building, —say a garage; B, B, the doors hinged to the wall A, at a. E represents the ceiling of the building, or other fixed support to which are fastened supporting brackets D. To the lower end of these

brackets D, a housing H is attached by bolts 1. The housing is in two parts, each part provided with flanges by which the two parts of the housing may be secured together 60 by means of screw bolts 3 or other convenient means. Each part of the housing is provided at one point with a circular extension 4, and, with journal bearings 5. The journal bearings accommodate a shaft 6, on

65 which is mounted, within the housing 4, a worm W. The shaft 6 extends through one of the bearings 5 and is supported near its outer end by a bracket 7 carrying a shaft bearing 8. Upon the outer end of the shaft 70 6 is a pulley P, over which is trained a belt 9, connecting the pulley P with a small pulley pinion 10, on the shaft 11 of the motor M; the motor being secured, as shown, to the top of the upper half of the housing H. 75 Arranged vertically in suitable bearings 12, 13, in the top and bottom parts of the housing H, is an operating shaft S, upon which is mounted, within the housing H, a worm gear G, in mesh with the worm W. Above 80 the hub shaft bearing 12 and mounted upon the shaft S, is a disc member 14 carrying on its under face two downwardly projecting cams K, K^a. On top of the housing H is a supporting standard 15 for a pivoted switch 85 lever 16, the free and vertically movable end of which lever 16 is in the path of the movable cams K and K^a.

17 is a housing containing a conventional switch of that well known and commercial 90 type wherein the circuit is closed, and which circuit is adapted to be opened by depressing the button 18. Intermediate its ends, the cam operated lever 16 is provided with an adjustable screw bolt 19, adapted to rest 95 upon the switch button 18. The switch is in the electric circuit, represented by the line 21, 21^a, connected with the motor M; the circuit being completed by the line 20. There may be such number of open switches 100 as are desired. I have illustrated three, which are indicated in Fig. 2, at 22, 22^a and 22^b. These will be located at convenient places; one, for example, may be placed outside the building. 105

The switches are in the electric circuit represented by the lines 21, 21^a, connecting with the motor M, the circuit being completed by the line 20.

110 It will be understood from the foregoing description that when the cam K is not resting on the switch lever 16, the switch 17 will

- be closed,--the current flowing over the line 21 through the switch 17, over the line 21^b to the motor. The motor will operate to actuate the shaft 6, worm W and worm gear G.
- 5 It will also be understood that as the shaft S rotates, the disc 14 carrying the cams K, K^a, will rotate one-half revolution and at the proper time one of the cams will engage the movable end of the lever 16, thereby de-
- 10 pressing the push button 18 opening the closed switch in the housing 17 to break the circuit, thus instantly stopping the motor. It will be understood that the disc 14 may be adjustably secured to the shaft S by ad-
- 15 justing the bolt 28 or other suitable means.

In order to start mechanism for another cycle of operation it will be necessary to relay the current around the now open switch in the housing 17. For this means I have provided a line 21 which is connected on one side direct to the line 21^b somewhere between switch 17 and motor M, and is connected with the line 21 by a plurality of standard push button switches 22, 22^a, etc., 20 the circuit being thus normally open. As shown, one side of these switches are connected with the line 21^b and the other side with the line 21. It will be understood that when any of these switches, say the switch 22, be pressed to close it, the current will be carried around the switch 17 as follows: over line 21, through switch 22, over line 21^b, to line 21^a, and to motor M. The motor instantly actuates the shaft S, as before explained, and the revolving disc 14 carrying the cams. The cam will thus be disengaged from the movable end of the lever 16, allowing the lever to raise to normal position, thus permitting the switch in the housing 40 17 to close. The current then passes through a switch 17 as previously described.

Referring now more particularly to the connection of the device just described, with the doors B, and having reference more particularly to Figs. 1, 2 and 3, I point out that T represents a suitable track or guide-way for a reciprocating member or members R, to which reciprocating members connecting rods 24 are pivotally secured at one end to the reciprocating member, and pivotally secured at their other end to the door or doors B. If there is but one door to operate, there will be but one push-and-pull rod 24. The reciprocating member R is actuated by a link L, connected at one end to the member R and at its other end to a crank arm C. The latter is mounted upon the shaft S, and when the shaft rotates, the free end of the part C swings in a familiar manner and pushes and then pulls the link L, so as to cause the familiar reciprocation, back and forth, in a straight line, of the reciprocating member R, in the guide-track T. This reciprocation would continue as long as the shaft rotates, but as before explained, the

cam K will actuate the switch 17, so as to stop the motor and therefore stop the movement of the reciprocating member R when it has reached the end of its movement in one direction. That is to say, if the parts 70 are in the position shown in Fig. 2, in full lines, when the switch 22 is closed, the reciprocation of the member R will be in a direction toward the doors B, and will continue slowly until it is in the position shown 75 in dotted lines in said Fig. 2. At this time the doors B will be open, their position and that of the push-and-pull rods 24 being indicated by the dotted lines.

The ratio of the teeth of the worm and the 80 worm gear and the co-relation of the parts is such that the cam K will cause the circuit to open and the parts to cease operation on the return movement to close the doors, precisely as and in the manner indicated above for the forward movement, to open the doors.

It will be understood that as the doors are swung only by the mechanism described, they will remain in their open or their closed 90 positions until the mechanism is again operated by the closing of one of the switches 22, 22^a, etc., the mechanism for operating the doors being the same as that which holds them in position until the mechanism is 95 again actuated by the closing of a switch.

The guide or track member T may be of any suitable material, and it is preferably connected to the housing H and supported at one end from the housing by the bracket 25. 100 The support for the other end of the guide track T is not herein indicated, but will be well understood.

It will be observed by reference to Fig. 1, that the mechanism above described is located above the top margins 26 of the doors B. While this is not strictly necessary, it is a preferred construction, and in order that the push-and-pull rods 24 may connect properly with the doors B, said rods 24 are 110 bent as indicated by the shade lines 27. Thus the ends of said rods 24 that are connected with the reciprocating member R are in horizontal plane of said member, while the ends 28 of said rods 24 are connected in 115 the lower plane of the top of the doors B. As shown in this instance, the ends 28 are connected at 29 to the top rail 26 of the doors B.

There may be occasion for disconnecting 120 the parts in order to operate the doors by hand from the inside of the building. I have, therefore, shown in Fig. 5, a slight modification of the reciprocating head R,--the same consisting of two tongue and grooved 125 parts 30, 31, secured together by a removable bolt 32 held in its position by a cotter pin 33. As shown in Fig. 5, the two members 30, 31, will be moved upward or away from the doors B, as the case may be, in the man- 130

ner hereinbefore described, when the motor is in operation. When it is desired to open or close the doors by hand, the cotter pin 33 will be removed, the bolt 32 drawn and 5 the parts 30, 31, disengaged.

In actual practice, I find it convenient to place one of the operating switches 22 outside of the garage or building equipped with my device, and in position where it may be 10 depressed to close the switch either by the foot or by the tire of a vehicle wheel. When this is done, the operator of an automobile may drive up to the garage, and by closing the switch 22, have the doors B open automatically, and drive into the garage; thereby avoiding the necessity of getting out of 15 the car in order to open the doors.

It will be understood that various changes may be made in the details of construction, 20 without departing from the principle of my invention; as for example, if but a single door B is to be operated, but one push-and-pull rod 24 may be used. I therefore do not desire to be limited to the specific 25 details herein shown excepting as set forth in the appended claims. Nevertheless, the mechanism illustrated is recommended as the result of successful operation, as being a practical and economical device; one which 30 will not readily get out of order.

I claim as my invention:

1. Operating means for a door, including, in combination with a fixed support and a hinged door, a housing, a rotatable shaft 35 therein, a worm gear on the shaft within the housing and a crank on the shaft outside the housing, an electric circuit including a motor and a switch, means for driving the worm gear from said motor, a guide track 40 connecting the housing with the fixed support, a member in the track and being in two parts, a link connecting the crank and said movable member, a push and pull bar connecting said member and the hinged door, 45 and removable means for holding the two parts of the movable member in operative relation.

2. Operating means for a door, including, in combination with a door frame and a door 50 hinged therein, a housing, a rotatable shaft extending through the housing, a worm gear on the shaft within the housing, an electric

circuit including a motor and a normally closed switch, means for driving the worm gear from the motor, a crank on the lower 55 part of the shaft below the housing, a guide track connecting the housing and the door frame, a member movable lengthwise in the housing, a link connecting the crank and said member, and a push and pull bar connecting said movable member and the door, and means governed by the rotation of the shaft for stopping the motor when the movable member has reached the end of its path in either direction, said lastmentioned means 60 including a cam on the shaft outside of the housing and a lever operatively positioned above and associated with said normally closed switch, with its free end adapted to be depressed by the cam to open said switch. 65

3. Means for operating doors, comprising in combination with a door frame and a door hinged therein, a two-part housing and means for supporting it, an operating shaft mounted therein and extending above and 75 below the housing, a worm gear on said shaft within the housing, a crank on the lower part of the shaft outside the housing, a worm within the housing in mesh with the worm gear, a motor on the housing, means for 80 operating the worm from the motor, an electric circuit, a switch for closing the same to actuate the motor, a normally closed switch in said circuit located on the housing in juxtaposition to the operating shaft, a movable cam adapted to be actuated by the rotation of the shaft, a lever on the housing above the normally closed switch, and adapted to be depressed by said cam to open 85 said normally closed switch, a guideway or track connecting the housing with the door frame, a member movable in the track, a link connecting said member with the crank, a push and pull bar connected to said member and to said hinged door and means for 90 supporting the track.

In testimony that I claim the foregoing as my invention I affix my signature, in the presence of two witnesses, this 28th day of April, 1921.

HARRY G. AINSWORTH.

Witnesses:

H. W. DENNSY,
C. FLACK.
